UNITED STATES PATENT OFFICE.

LUKE CHAPMAN, OF COLLINSVILLE, CONNECTICUT, ASSIGNOR TO HIMSELF
AND THE COLLINS COMPANY, OF SAME PLACE.

IMPROVEMENT IN GANG-PLOWS.

Specification forming part of Letters Patent No. 120,572, dated November 7, 1871.

To all whom it may concern:

Be it known that I, LUKE CHAPMAN, of Collinsville, in the county of Hartford and State of Connecticut, have invented an Improved Gang-Plow, of which the following is a specification:

This invention is an improved apparatus for agricultural use, for plowing with two or more plows at the same time, turning two or more furrows in the earth at once. It is more particularly intended for use with steam traction-engines, though of course any other power may be applied.

Figure 1 is a side elevation, with the wheels and axle in an exactly reverse position from that of actual use for the purpose of better showing the form and arrangement of the various parts. Fig. 2 is a plan view of the gang-plow in the same position as in Fig. 1. Fig. 3 is a detached view of the standard which rises immediately from the axle, together with the devices for lifting the plows, for reversing the sets of plows, and for oscillating them horizontally. Fig. 4 is a detached enlarged view of the reverse side of the parts shown in Fig. 3.

The letter *a* indicates the beam to which the plows are hung, made preferably of a hollow metal tube, on one side of which is attached a set of two or more right-hand plows, *a*¹ *a*¹. On the exactly opposite side is attached a similar set of left-hand plows, *a*² *a*². Both sets are attached to the beam at such an angle as will make their landsides point straight forward when the plows are at work. As this beam is reversible, it is not positively necessary that the sets of plows should be opposed to each other, for it is manifest that the sets might be placed at right angles or other angles; but it is preferred that they should be placed opposite for the purpose of balancing each other. Neither is this invention limited to just the arrangement and kind of plows indicated above, for, with a reversible beam and the other combined mechanical devices, it is adapted to all kinds and degrees of plowing; for instance, sets of alternate right-and-left-hand plows may be opposed to each other for the purpose of cultivating crops after the first breaking, turning back-furrows, or in preparing soil specially for special crops; and suitable arrangements will also suggest themselves for trench, ridge, and other kinds of plowing, and for all kinds of work now done by double-furrow and shovel-plows and cultivators. The beam *a* is hung in the swivel *b*,

which turns in the sliding block *b*¹ running through the same, and collared upon either side thereof so that it cannot escape therefrom. The worm-gear *c* forms the rear one of these collars, and into it meshes the worm *c*¹, which is upon the shaft *c*², hung in bearings *c*³, attached to the upper corners of the sliding block, and actuated by the crank-arm *c*⁴, by means of which the operator of the machine can reverse the positions of the two respective sets of plows and put either set at work, as he desires. The sliding block *b*¹ slides vertically on ways in the open interior of the standard *d*. It is suspended from the top of the standard by means of a hydraulic lifting-jack, composed principally of the exterior parts, barrel *d*¹, piston-rod *d*², and handle *d*³. Of course this sliding block and its dependent plows might be suspended herein by a screw or other common lifting device of great power; but the device presented is the one preferred for its power and ease of operation. By means of this hydraulic jack the plows can be raised or lowered by the operator, as desired. The standard *d* at its foot rests on and is attached to the bed-plate *f*, which is pivoted horizontally on the axle-plate *f*¹, just beneath it, which latter is firmly fastened to the axle *g*. At one side, on the outer circumference of the bed-plate *f*, is hung the shaft *f*², actuated by the crank *f*³, and having a worm, *f*⁴, thereon, meshing into the worm-teeth *f*⁵ attached to the axle-plate *f*¹, whereby the operator may oscillate the bed-plate *f*, and with it the standard and plows, so as to make the beam *a* observe any desired angle with the axle *g*. On the outer circumference of the axle-plate *f*¹ are three stop-marks, *i* *i*¹ *i*², which will be traveled over by the printed end *f*⁶ of the bed-plate *f* when it is revolved horizontally on the axle-plate *f*¹. These three stop-marks indicate the three positions which it is desirable for the beam *a* to observe with reference to the axle *g* at different times. When the pointer *f*⁶ is on the stop, mark *i*¹ the beam is at right angles to the axle and is in position for being drawn from one place to another, the drawing power being attached at the front end *a*³ of the beam. When the pointer *f*⁶ is upon the stop-mark *i* and the set of right-hand plows is undermost, the machine is in the proper position for putting this set of plows at work. When the pointer *f*⁶ is upon the stop-mark *i*² and the set of left-hand plows is under-

most, then the machine is in position for putting this set of plows work. When the pointer f^6 is upon the stop-mark i^1 and it is intended to move the plow from one place to another, then the beam a should be turned so as to have both sets of plows project out horizontally therefrom. From the front end of the beam a the arc of a circle, o , extends, whose center is directly over the pivot which attaches the bed-plate f to the axle-plate f^1 , and on this arc slides the band o^1 , which can be set at any point on the arc by the set-screw o^2 , and to the front of which is attached a link, o^3 , to which the drawing power is to be attached when the machine is at work. From the back of the band o^1 a draw-rod, o^4 , runs back to near the standard d and attaches to the beam a . Practically the band o^1 is set at such a point on the arc o that the draw-rod o^4 will be straight over the line of draft when the plows are at work. Just in front of the plows is a gauge-wheel, m , attached by the crank-arm m^1 to the beam a , and its shaft m^2 running through the beam a and firmly attached to the circular plate n , which has a lock-pin, n^1 , which can be moved out and in, and abutting against a circular face on the projection s , in which circular face is a number of round holes, into which the inner end of the lock-pin n^1 can catch, so as to lock the wheel m at any desired point in its revolution around the shaft m^2 , thus regulating the height at which the front end of the beam a shall be from the ground. When the sets of plows are reversed the position of this gauge-wheel m is to be correspondingly

reversed. The axle g is hung below the centers of the wheels $x x$ by means of arms $g^1 g^2$. The parts are all of metal.

I claim as my invention—

1. The beam a , made reversible, and provided with sets of plows both before and behind the point of suspension, substantially as described.

2. The reversible beam a combined with the swivel b , sliding block p^1 , and standard d , and made rotary by means of the worm-gear e and worm e^1 , substantially as described.

3. The parts as claimed in the immediately preceding clause, combined with the lifting-jack described, substantially as described.

4. The standard d having a reversible beam a hung therein, and made oscillatory sidewise upon the main axle g by means of the belt-plate f pivoted to the axle-plate f^1 , and the worm f^4 and worm-teeth f^5 , substantially as described.

6. In combination with a reversible plow-beam, a , the gauge-wheel m , attached adjustably thereto, substantially as described.

7. A plow-beam, a , made reversible by mechanism substantially as described, made adjustable vertically and sidewise by mechanism substantially as described, and the whole hung on a main axle, g , permanently sunk below the level of the centers of the supporting-wheel, substantially as described.

LUKE CHAPMAN.
